COMPRESSOR

Fred M. McCracken, Norwood, Ohio

Application May 29, 1933, Serial No. 673,393

10 Claims. (Cl. 230—145)

This invention relates to compressors in general but more particularly to a compressor suitable for compressing a chemical gas such as used in domestic and other refrigerating devices but it will be understood that it may be used for other compression purposes as well.

Heretofore, two different principles of compressors have generally been used for this purpose—the reciprocating piston type and the rotary type. The piston type of compressor has usually been driven by a belt from a power device, such as an electric motor, and this arrangement enabled the use of a fan on the motor shaft to provide a forced draft for cooling the condenser of the refrigeration device but it made necessary the use of a shaft seal around the shaft of the compressor to prevent escape of the gas from within. Such seals have invariably given considerable trouble and proven very unreliable. Other piston types of compressors have been directly connected to the motor and both motor and compressor hermetically sealed in a container with the gas thus obviating the requirement for a shaft seal but this arrangement did not permit of the use of a fan draft for cooling the condenser, and it had the added disadvantage that the motor could not be serviced without unsealing the container and thereby liberating the gas. The rotary type of compressor, being usually directly connected to the motor, was not favorable to the use of a shaft seal because of the high speed of the shaft and therefore this type of compressor, together with the motor could not be serviced without destroying the seal confining the gas. Another disadvantage of both the piston type and the rotary type of compressor is that an enormous amount of power is wasted in overcoming the friction of the moving parts even with the best of workmanship and good lubrication and in the piston type of compressor there is an additional waste of power due to starting and stopping the reciprocating parts at each end of their stroke which occurs many hundreds of times per minute. Furthermore, friction inevitably results in wear on the parts and consequent loss of efficiency in compression thus making service and replacement of parts frequently necessary in order to maintain satisfactory performance, and the expense incident thereto greatly increases the cost of electric refrigeration to the user or places a serious burden on the manufacturer or dealer.

One object of this invention therefore is to provide a compressor that is devoid of any reciprocating parts, such as pistons or cylinders,

or of any revolving parts, such as the eccentrics, rollers or blades common to rotary types of compressors thereby eliminating the friction and resultant wear incident thereto, conserving power and effecting real economy in operating and maintenance expense.

Another object is to provide a compressor which can be hermetically sealed independent of the power device thus having the shaft of the power device available for the application of a fan to provide a forced draft for cooling a condenser and also thus avoiding the use of a shaft seal so that the power device may be readily replaced or serviced without liberating any of the refrigerating gas.

Another object is to provide a compressor that can be directly connected to the actuating member of a power device (such as the shaft of an electric motor) without the use of a clutch, coupling or any "tied-up" connection.

Another object is to provide a compressor having only one major power-actuated element directly adapted to effect compression of the gas, thus making for simplicity and low cost of manufacture.

Another object is to provide a compressor that is devoid of any load bearing within the chamber or passages containing the refrigerating gas.

Another object is to provide a compressor that has only one load bearing.

Another object is to provide a compressor of compact form yet easily assembled and the parts thereof readily accessible for examination or replacement.

Another object is to obtain a higher degree of volumetric efficiency than that which is possible with other types of compressors.

These and other objects will be apparent from the following description and the accompanying drawings which illustrate a preferred form of the invention.

My invention will be further readily understood from the following description and claims and from the drawings, in which latter:

Fig. 1 is an external side elevation of the compressor unit and the attached power device.

Fig. 2 is an end elevation of the same as viewed from the compressor end.

Fig. 3 is a sectional elevation through the compressor unit taken substantially on a line 3—3 of Fig. 2.

Fig. 4 is a sectional view taken on the line 4—4 of Fig. 3.

Fig. 5 is a sectional view taken on a line 5—5 of Fig. 3.

Fig. 6 is a sectional view taken on the line 6—6 of Fig. 3.

Fig. 7 is a sectional view taken on a line 7—7 of Fig. 3.

5 Figs. 8, 9 and 10 are comparative views to Fig. 4 and show the relative positions of the compression elements at different stages of the cycle of movement.

10 Fig. 11 is a profile view of the discharge valve disc.

Fig. 12 is a perspective view of the blade or division bar.

Fig. 13 is a longitudinal section of a modified form of compressor unit.

15 Fig. 14 is a sectional view taken on a line 14—14 of Fig. 13.

20 Figs. 15, 16 and 17 are sectional views taken on the line 15—15 of Fig. 13, and, in connection with Fig. 14, show the relative positions of the compression elements at different stages of the cycle of movement.

25 In the drawings, 20 represents a compressor housing having a portion 21 arranged for attachment to any suitable structure by means of bolts or otherwise.

30 The body portion of the housing 20 is preferably of cylindric form and rigidly attached to one end thereof is a cap or head plate 22 which is secured by means of screws 23. The cap plate 22 not only serves as a closure for that end of the housing but also as one of the side plates for the compression chamber 24 and as a mounting plate for the cylinder 25 and the other side plate 26 which are secured to the plate 22 by means of the screws 27. This assembly consisting of the cylinder 25 and the plates 22 and 26 may be termed the "cylinder unit" and in order that the annular location thereof relative to the housing 20 may be established with precision, 40 the said housing is bored out to an accurate diameter and the cylinder 25 is accurately positioned therein concentric to the outside diameter so that the axis thereof coincides with the axis of the bore in the housing.

45 Positioned within the cylinder 25 and laterally confined between the plates 22 and 26 is a movable member 28 of cylindric form which, in the absence of a more appropriate term, may be called the "eccentric" merely because it is normally positioned and held eccentrically within the cylinder, that is, the axis of the "eccentric" is spaced from the axis of the cylinder 25 a distance equal to exactly one half the difference between the diameter of the cylinder bore and 55 the diameter of the "eccentric" so that the peripheral surface of the "eccentric" is thus in contact with the wall of the cylinder.

55 The eccentric 28 is provided with a hub-like portion 29 concentric thereto which extends laterally through an opening 30 concentrically located in the plate 26 and comprises a flange 31 and a threaded tenon 32. The eccentric 28 is further provided with a detachable cup-like extension 33 which is concentrically mounted on 60 the tenon 32 and held securely against the face of the flange 31 by a jam nut 34. The extension 33 has a flange 35 to which is rigidly secured one end of a cylindric metal bellows or "sylphon" 36 which has its other end similarly attached to the plate 26. Thus there is provided a gas-tight connection of conduit form, axially flexible but torsionally rigid, between the cylinder 25 which is stationary and the eccentric 28 which is movable.

75 Attached to the housing 20 at the end thereof

opposite the cylinder unit, is a power device 37, here shown as an electric motor having a rotary shaft 38 and bearing caps 39 and 40 which support said shaft.

5 In order that the annular location and alignment of the shaft 38 relative to the cylinder 25 may be established with precision, the housing 20, at the motor end, is bored out to an accurate diameter and exactly concentric with the bore at the other end which positions the cylinder and the cap 40 is provided with a flange 41 which is accurately machined for a snug fit in the housing and exactly concentric to the bore of the bearing member 42 secured in the cap 40 for supporting the shaft 38. Thus the axis of the 15 said shaft is established exactly concentric and in alignment with the axis of the cylinder 25. The motor 37 is secured to the housing 20 by the screws 43 which extend through ears 44 on the housing and are threaded into the cap 40. 20

The shaft 38 is so arranged that the rotation thereof will cause movement of the "eccentric" 28—not rotary movement because the said eccentric is restrained from any rotary movement by its connection to the plate 26 through the 25 bellows 36 but the movement is a gyratory movement of the "eccentric's" axis around the axis of the cylinder. This is accomplished by rotatably supporting the eccentric 28 at its axis on a cylindric extension 45 of the shaft 38, the axis of the 30 said extension being eccentric to the axis of the said shaft and the radial distance between the said axes being equivalent to one half the difference between the diameter of the bore in the cylinder 25 and the diameter of the eccentric 28 35 so as to hold the eccentric 28 eccentrically within the said bore to such an extent that the peripheral surface of the eccentric 28 is in contact with the wall of the cylinder, as previously referred to. Thus, as the shaft 38 rotates, the 40 eccentric 28 is caused to "walk-around" within the bore of the cylinder 25, always in peripheral contact with the wall of the cylinder and held in constant peripheral relation thereto by the torsionally rigid sylphon 36.

45 In order to utilize this movement for compressing a vapor or gas, there is provided a blade or division bar 46 which is preferably confined in a radial slot 47 in the eccentric 28 and yieldingly held into contact with the wall of the cylinder 50 25 by compression springs 48, the said blade being angularly located intermediate an intake port 49 in the eccentric 28 and a discharge valve 50 in the cylinder 25 thus serving as a wall to separate the intake from the discharge port. By 55 this arrangement, gas enters the chamber 24 on one side of the blade 46 through the port 49 and is discharged therefrom on the other side of the blade through the valve 50 which comprises a port-hole 51 normally closed by a disc 52 under 60 the influence of a compression spring 53 which is located in a chamber 54 and confined between the said disc and a retaining screw 55 mounted in the cylinder 25. The force of the compressed gas acting upon that portion of the surface of 65 the disc 52 which is exposed thereto through the port-hole 51 causes the said disc to move against the action of the spring 53 and thus permit the compressed gas to pass through the said port-hole into the chamber 54. In order that the 70 movement of the disc 52 may be limited to a desirable extent, the screw 55 is provided with a cylindric extension 56 of proper length and this also serves as a pilot for the spring 53 to hold it in correct position.

Figs. 4 and 5 show the position of the eccentric 28 when the chamber 24 is equally divided by the blade 46, that is, when substantially half a charge of gas has been taken into the chamber on one side of the blade and compression on the other side has been half accomplished. When the eccentric is in this position, the point of contact between the said eccentric and the wall of the cylinder 25 is opposite the blade 46 on a direct line through the center of the blade and the axis of the said eccentric and the axis of the cylinder 25 is also on said line intermediate the blade and the eccentric's axis.

Figs. 8, 9 and 10 show the position of the eccentric 28 at different stages in its cycle of movement. For example: When the shaft has rotated clockwise substantially 90 degrees from the position shown in Fig. 5, the axis of the said eccentric has thus been moved 90 degrees clockwise around the axis of the cylinder 25 to the position shown in Fig. 8 resulting in nearly full accomplishment of compression and discharge on that side of the blade and almost a full charge of gas in the chamber on the intake side of the blade.

A further 90 degree movement of the shaft 38 brings the eccentric into the position shown in Fig. 9 wherein compression has been fully accomplished and the chamber 24 supplied with a full charge of gas compression of which is about to begin on the discharge side and a new charge about to be taken in on the intake side.

A still further 90 degree rotation of the shaft 38 will result in positioning the eccentric as shown in Fig. 10 wherein partial compression has taken place on the discharge side and a partial charge of gas taken in on the intake side.

The complete cycle of movement of the eccentric 28 will have been accomplished with a further 90 degrees of rotation of the shaft 38 resulting in the said eccentric again occupying the position shown in Fig. 5. Each rotation of the shaft 38 will thus effect one complete cycle of movement of the eccentric 28, that is, one full planetary circuit of the said eccentric's axis around the axis of the cylinder 25, resulting in one full charge of gas being compressed and discharged and another full charge being taken in.

In order that gas may be conducted from the cooling element of a refrigerator (when the device is thus applied), or from any other source, to the intake port 49 of the compressor, the plate 22 may be provided with a suitable fitting such as 51 which is arranged for connection with said cooling element by tubing or otherwise. Openings 58, 59 and 60 arranged respectively in plate 22, cylinder 25 and plate 26 provide a passage-way for the gas from the fitting 57 into the chamber within the bellows 36 from whence it may pass to the intake port 49 through an opening 61 which extends longitudinally through the eccentric 28 from the flange 34 to the face adjacent the plate 22. The intake port 49 is shown as 65 comprising a channel recess in the side face of the eccentric 28 and may, if desired, be arranged in duplicate, one port on each side of the eccentric as shown.

Transit of the compressed gas from the discharge valve 50 may be provided for by a passage-way comprising openings 62 and 63 arranged respectively in cylinder 25 and plate 22, the opening 62 communicating with the valve chamber 54 and opening 63 with a suitable fitting such as 64 which 75 is arranged for connection, by tubing or other-

wise with the condenser of a refrigerator or other device.

In order to provide ample lubrication for the bearing of the eccentric 28 on the shaft extension 45 and also for the bearing 42 of the shaft 38, 5 the chamber within the housing 20 may contain oil in sufficient quantity to immerse both bearings, in which case the cap 40 is provided with a suitable oil retainer or seal 65 to prevent escape of oil around the shaft into the motor. 10

Inasmuch as an induced draft of circulating air is advantageous for radiating generated heat from the motor and compressor and as a forced draft is practically necessary for efficient cooling of the condenser coil, the free end of the motor shaft 38 is provided with a fan 66 to serve this purpose. 15

The modified form of the compressor unit shown in Figs. 13 to 17 inclusive embodies the same basic idea hereinbefore described and performs the function of compression in a manner which accomplishes similar results. The practical difference herein resides principally in the reversal of the primary elements—the cylinder being movable and the "eccentric" being stationary. 25

In this instance, 70 represents the compressor housing having a portion 71 for mounting purposes. Rigidly attached to one end of the housing is a supporting cap 72 which is snugly fitted 30 into a bore in the housing and secured by means of screws 73. The cap 72 is provided with an extension 74 to support the "eccentric" 75 which is of cylindric form and comprises a portion 76 having an extension 77 by which the said eccentric is supported and securely held in the bore 78 in the cap extension 74 thus positioning the said eccentric exactly concentric to the bore in the housing 70.

The "cylinder unit", comprises the cylinder 79 40 and side plates 80 and 81 which enclose the compression chamber 82 and which are secured together by screws 83. Rigidly secured to plate 81 is one end of a cylindric metal bellows 84 which has its other end similarly attached to the cap 72. Thus there is provided a gas-tight connection of conduit form, axially flexible but torsionally rigid between the eccentric 75 which is stationary and the cylinder 79 which is movable. 45

The motor cap 85 is mounted on the end of the 50 housing 70 and carries a bearing 86 which supports the motor shaft 87.

In order that the annular location and alignment of the shaft 87 relative to the eccentric 75 may be established with precision, the housing 55 70 at the motor end is bored out to an accurate diameter and exactly concentric with the bore at the other end which positions the eccentric and the cap 85 is provided with a flange 88 which is accurately machined for a snug fit in the housing 60 and exactly concentric to the bore of the bearing member 86. Thus the axis of the shaft 87 is established exactly concentric and in alignment with the axis of the eccentric 75. The motor cap 85 is secured to the housing 70 by the screws 89 65 which extend through ears 90 on the housing and are threaded into the cap.

Rotation of the shaft 87 causes a gyratory movement of the cylinder's axis around the axis of the eccentric. This is accomplished by rotatably supporting the plate 80 at its axis on an extension 91 of the shaft 87 said extension being eccentric to the axis of the said shaft in amount sufficient to hold the cylinder 79 eccentric to the "eccentric" 75 to such an extent that the 75

peripheral surface of the said "eccentric" is in contact with the wall of the said cylinder. Thus, as the shaft 87 rotates, the "cylinder unit" is caused to "walk-around" the eccentric 75 always maintaining peripheral contact between the said eccentric and the wall of the cylinder and held in constant peripheral relation thereto by the torsionally rigid sylphon 84.

In this instance, the blade or division bar 92 is shown as being confined in a radial slot 93 in the cylinder 79 and yieldingly held into contact with the eccentric by compression springs 94, the point of contact being substantially midway between the intake port 95 and discharge valve 96 both of which are positioned in the eccentric 75. By this arrangement, the gas enters the chamber 82 on one side of the blade 92 through the port 95 and is discharged therefrom on the other side of the blade through the valve 96 which comprises a port-hole 97 normally closed by a disc 98 under the influence of a compression spring 99 which is located in a chamber 100 and confined between the said disc and the bottom wall of the said chamber. The port-hole 97 is embodied in a disc 101 which is securely held in a recess in the eccentric 75. The force of the compression acting upon that portion of the surface of the disc 98 which is exposed thereto through the port-hole 97 causes the said disc to move against the action of the spring 99 and thus permit the compressed gas to pass through the said port-hole into the chamber 100. So that the movement of the disc 98 may be limited to a desirable extent, the chamber 100 is formed with a central stem 102 of proper length and this also serves as a pilot for the spring 99 to define its position.

In order that gas may be conducted from an external source to the intake port 95, the cap 72 may be provided with a suitable fitting 103 for tube connection and an opening 104 in the said cap may provide a passageway for the gas from the said fitting into the chamber within the bellows 84 from whence it may pass to the said port through an opening 105 which extends longitudinally through the eccentric 75 from the extension 77 to the face adjacent the plate 80. Here also, the intake port 95 is shown as arranged in duplicate, one port on each side face of the eccentric.

Transit of the compressed gas from the valve 96 may be provided for by a passageway 106 extending radially through the eccentric 75 and communicating at its outer end with the chamber 100 through an opening 107 in the wall of the stem 102 and at its inner end with a passageway 108 extending longitudinally through the eccentric 75 to the bore 78 and thence through an opening 109 to a suitable fitting 110 mounted in the cap 72 and arranged for tubing connection with the device to be served.

Figs. 14, 15, 16 and 17 show the position of the cylinder 79 at different stages in its cycle of movement. Fig. 14 shows the position when half a charge of gas has been taken into the chamber on one side of the blade and compression on the other side has been half accomplished. Fig. 15 shows the position when the shaft 87 has rotated clockwise 90 degrees from the position shown in Fig. 14 thus moving the axis of the cylinder 79 an equivalent amount around the axis of the eccentric 75. Fig. 16 shows the position after an additional 90 degrees of movement and Fig. 17 shows a still further movement of 90 degrees. It will thus be seen that a complete rota-

tion of the shaft 87 will effect a complete cycle of movement of the cylinder 79, that is, one full planetary circuit of the cylinder's axis around the axis of the eccentric 75, resulting in one full charge of gas being compressed and another full charge being taken in.

Ample lubrication for the bearing of the plate 80 on the shaft extension 91 and also for the shaft bearing 86 may be provided for by charging the housing 70 with sufficient quantity of lubricating oil to immerse both bearings. To prevent escape of any of such oil around the shaft into the motor, the cap 85 may be provided with a suitable oil seal 111.

From the foregoing, it will be apparent that I have provided a compressor which accomplishes, in a novel and practical manner, all of the objectives stated herein.

It is to be understood that the disclosure made herein is a preferred form and that the various elements of the device may be modified to suit particular requirements without departing from the spirit and scope of the invention as set forth in the following claims.

Having thus fully described my invention what I claim as new and desire to secure by Letters Patent, is:

1. A compression device comprising a member having a cylindric chamber, a cylindric member enclosed within said chamber and disposed eccentric thereto, an intake port in one of said members, a discharge port in one of said members, a blade movably mounted in one of said members, yieldingly held into peripheral contact with the other of said members and positioned radially intermediate said ports, said members thus functioning as a pump when one member is held stationary and the other member is given a gyratory motion relative thereto, sealed connecting means between said members comprising a vapor-tight flexible tube arranged so that the chamber therewithin receives leakage of vapor from the compression chamber of said pump thus preventing escape thereof to the atmosphere, and a device to actuate said other member in a gyratory manner.

2. A compression device comprising a stationary cylindric member, a movable cylindric member, one of said members encompassing the other and arranged with its axis parallel to the axis of said other member but displaced relative thereto, an intake port in one of said members, a discharge port in one of said members, a blade movably mounted in one of said members, yieldingly held into peripheral contact with the other of said members and positioned radially intermediate said ports, said members thus functioning as a pump when said movable member is given a gyratory movement, a vapor-tight flexible tubular structure attached at one end to said stationary member and having its other end hermetically connected direct to said movable member, said structure being arranged so that the chamber therewithin receives leakage of vapor from the compression chamber of said pump thus preventing escape thereof to the atmosphere, and a device to actuate said movable member in a gyratory manner.

3. In a compressor mechanism, the combination of a member comprising spaced end walls and having a cylindric chamber enclosed therebetween, a cylindric member confined between said walls and disposed eccentrically with relation to said chamber, one of said walls having an aperture located axially therein and said cyl-

5 indric member having an axially disposed extension projecting through said aperture and terminating in a portion remotely spaced from said apertured wall, one of said members being stationary and the other being arranged for gyratory movement relative thereto whereby vapor may be compressed within said chamber, a vapor-tight flexible tubular structure encompassing said extension and having one end hermetically connected to said remote portion thereof and having its other end hermetically connected to said apertured wall, said aperture communicating with the chamber within said tubular structure, said structure acting to prevent rotation of said movable member about its axis without restricting gyratory movement thereof, said structure also serving as a seal to prevent escape to the atmosphere of compressed vapor which may pass between said cylindric member and said apertured wall and through said aperture, and a device to actuate said movable member in a gyratory manner.

4. In a gyratory compressor, the combination with a cylinder member and an eccentric member, 25 one of which is stationary and the other movable in a gyratory manner, of a vapor-tight flexible tubular structure having one end hermetically connected to said stationary member and the other end hermetically connected to said movable member, said structure acting to prevent rotation of said movable member about its axis without restricting its freedom to gyrate and being arranged in relation to said members so as to receive within said tubular structure leakage of 35 vapor from the compression chamber of said compressor and thus serve as a seal to prevent escape of said vapor to the atmosphere.

5. The combination with a gyratory compressor mechanism comprising a cylinder member provided with end walls and an eccentric member confined therebetween, of hermetically attached connecting means joining said cylinder member to said eccentric member, said means comprising a vapor-tight flexible tubular structure arranged 45 in relation to said members so that compressed vapor escaping between said eccentric member and the surface of the end wall adjacent to said structure will be confined by and within said structure which thus serves as a seal to prevent escape of said vapor to the atmosphere.

50 6. Means for sealing a gyratory compression mechanism comprising a cylinder element and an eccentric element confined therewithin, which consists in the provision of a vapor-tight tubular structure, axially flexible but torsionally non-flexible, said structure being hermetically connected at one end to said cylinder element and hermetically connected at its other end to said eccentric element, and being arranged in relation to said elements so that the chamber within said structure will receive leakage of vapor from the compression chamber of said compression mechanism and thus said vapor will be confined by and within said structure so that it may be available for 60 delivery to the said compression chamber.

65 7. In a gyratory compressor mechanism where- in vapor is compressed within a cylinder element

by an eccentric element as a result of gyratory motion of one of said elements, the combination of an intake passageway through which vapor may be conducted to the compression chamber within said cylinder element, and hermetically sealed connecting means joining said cylinder element to said eccentric element, said means comprising a flexible tubular structure arranged in relation to said elements so that leakage of vapor from said compression chamber will be received by and within said tubular structure, said tubular structure having communication with said passageway whereby said leakage may be returned to said compression chamber.

8. In a gyratory compressor mechanism where- in vapor is compressed within a cylinder element by an eccentric element as a result of gyratory motion of one of said elements, an intake passageway through which vapor may be conducted to the compression chamber within said cylinder element, said passageway comprising a flexible tubular structure having one end hermetically connected to said cylinder element and the other end hermetically connected to said eccentric element, said tubular structure being arranged in relation to said elements so that leakage of vapor from said compression chamber will be received within said passageway so that said leakage may be returned to said compression chamber.

9. Means for sealing a gyratory compression mechanism comprising a cylinder element having a compressor chamber and an eccentric element confined therewithin, which consists in the provision of connecting means between said elements comprising a vapor-tight axially flexible but torsionally rigid tubular structure and a fully rigid cylindric structure, one of said structures freely encompassing the other, said cylindric structure being hermetically connected at one end to one of said elements and similarly connected at its other end to one end of said tubular structure, the other end of said tubular structure being hermetically connected to the other of said elements, said structures being arranged in relation to said elements so that the free space between said structures will receive leakage of vapor from the compression chamber of said compression mechanism and thus said vapor will be confined by and within said connecting means so that it may be available for redelivery to the 50 said compression chamber.

10. The combination with a gyratory compressor mechanism comprising a cylinder member provided with end walls and an eccentric member confined therebetween, of hermetically attached cylindric connecting means joining said cylinder member to said eccentric member, said means comprising a vapor-tight flexible tubular structure and being arranged in relation to said members so that compressed vapor escaping between 55 said eccentric member and the surface of the end wall adjacent to said connecting means will be confined by and within said means which thus serves as a seal to prevent escape of said vapor to the atmosphere.

65 FRED M. McCACKEN.
